UNITED STATES PATENT OFFICE.

SIGURD E. ANDERSON, OF DES MOINES, IOWA.

SILO-REINFORCEMENT.

1,077,949.

Specification of Letters Patent.

Patented Nov. 4, 1913.

Application filed June 16, 1913. Serial No. 773,862.

To all whom it may concern:

Be it known that I, SIGURD E. ANDERSON, a citizen of the United States, and residing at Des Moines, in the county of Polk and State of Iowa, have invented certain new and useful Improvements in Silo-Reinforcement, of which the following is a specification.

It is the object of the present invention 10 to provide improved reinforcing means for silos and more particularly for providing the reinforcement at and near the door opening, the arrangement being such that an adequate number of tie-rods may encircle 15 the entire silo and may coöperate not only in giving rigidity to the structure as a whole but also in giving firmness and security at and near the door openings.

While my invention is of general application in silo construction, it has been found 20 particularly advantageous in connection with silos built up out of cement staves or blocks for with such a construction, the staves are relatively short and the difficulty 25 of securing rigidity and air-tight construction are of a different character from those made with any wood stave construction.

According to my present invention, a 30 metal frame is provided of a shape and size to completely encircle the door opening and so positioned and constructed as to strengthen and reinforce the edges of the opening wall at the same time affording ready means for attachment to a hoop encircling the 35 tire silo with the objects in mind of stiffening the silo at a zone, where a hoop could not ordinarily be placed and of stiffening the door with means tied in as a part of the main silo reinforcement. The door 40 member itself may be of the usual construction put in place from the inside and having attaching means of usual form for gripping the metal edges of the frame embodied in the present invention.

45 The details and further objects of the invention will be better understood from the following detailed description which is to be taken in conjunction with the accompanying drawings wherein—

50 Figure 1 illustrates a section of a cement or concrete stave silo with two door openings reinforced, the doors themselves being removed to expose the dark interior of the silo. Fig. 2 is a fragmentary section through 55 one of the door openings. Fig. 3 is a detail of the hoop attachment, and Fig. 4 is a

perspective view of one of the door opening reinforcements.

The silo here illustrated is built up of cement or concrete staves 1 shaped at their edges as shown in Fig. 2 so that they will fit together with tight joints somewhat in the nature of tonguing and grooving. The structure may be built up to any desired height and with many more door openings than appear in Fig. 1.

The portion of the silo wherein the door openings are located is preferably built up not of narrow staves as throughout the body of the silo, but of wide blocks 2 as wide for instance, as three of the staves and shaped with openings so positioned that when these large blocks are set one above another, there will be formed an opening say three feet high and two feet broad. Preferably these blocks are U-shaped and two of them alone are necessary for each door opening. In other words the broad U-shaped blocks are placed with their openings contiguous to one another. It is to such a construction that the reinforcement hereinafter disclosed is particularly adapted.

The reinforcement itself is illustrated in perspective in Fig. 4 and comprises a pair of iron or steel bands 3 and 4 bent at their ends as shown and connected together at their ends by angle irons 5 and 6, each of which is bent back at its end portions 7 and 8 for more ready and secure attachment to the adjacent end of the metal strip. The strip itself may be offset at 9 and riveted directly to the outer face of the base portion of the angle iron. The frame thus built up out of the two strips 3 and 4 and their connecting angle plates 5 and 6 is in general of hexagonal form and its inner face can lie directly against the wall of the silo throughout the entire extent of the frame and so by direct contact can reinforce the silo throughout a wide area. By giving to 100 the angle plates 5 and 6 a lateral or transverse bend, not only is a secure seat afforded for the riveted and offset ends of the bands 3 and 4 but the corners of the hexagonal frame are materially strengthened and stiffened and owing to the heavy strains applied to the frame at these points, this additional stiffening becomes a feature of importance. The outstanding edge or face of the angle plate is perforated to receive the 110 end of a tie-rod 10 threaded on its end to receive an adjusting nut and encircling the

silo and adjustably secured to the other side of the frame by a tightening and adjusting nut 12. It is the function of this tie-rod or hoop 10 to reinforce the silo staves 5 through the entire girth of the cylinder and it is also its function to hold the reinforcing frame in place and to give to it stiffness and security of position. The adjusting nuts 11 and 12 permit a variation in the tension on 10 the tie-rod and also allow for lateral shifting of the frame with respect to the door opening so that an easy means is afforded for initially bringing the frame into correct alignment with the opening and for keeping it in alignment at all times irrespective of such changes as might go on in the silo due to settling or age.

To prevent possible collapse of the frame under the heavy pull of the tie-rod 10, stiffening braces 13 and 14 are provided, these 20 preferably being in the form of heavy rods flattened at their ends for attachment to the upper and lower corners of the frame by rivets 15 as shown in Fig. 4. This flattening of the ends in fact offsets the rod with 25 respect to the silo wall so that the inner edge of the rods may lie directly in contact with the cement and yet their flattened ends may be spaced from the cement by a distance 30 equal to the thickness of the metal strips 3 and 4 of the frame. Thus not only do the rods 13 and 14 serve to stiffen the frame but by lying directly in contact with the cement along the edges of the door opening they 35 stiffen those edges and strengthen them to resist the strong outward thrust of the door particularly when the ensilage is green and is fermenting under which conditions the hydrostatic and gas pressure on the inside 40 may be very high.

The door itself not shown in the drawings may be of usual construction fitted into the offset seats 16 of Fig. 2 and extending through between rods 13 and 14 and provided on its outer face with suitable tightening means and clasps for gripping the rods 13 and 14 to hold the door firmly to its seat in the concrete.

It will be seen that with the construction 50 above disclosed the silo is adequately reinforced even around the zone in which each door opening lies and yet no tie-rod crosses the door opening or obstructs in any way the free removal of ensilage through that 55 opening. The reinforcing frame stiffens the wide blocks which encircle each opening and may overlap onto the adjacent staves making the structure around the door as strong or stronger and even more rigid than parts 60 of the silo remote therefrom. In this respect the reinforcing frame here disclosed and its mode of attachment to the structure is particularly advantageous when used in connection with a cement or concrete stave silo as 65 herein set forth, although it may be used to

advantage in other relations as will be apparent to those skilled in the art.

The various details of construction and arrangement of parts may be changed and the construction may be variously modified without departing from the spirit of the invention as defined by the appended claims.

Having thus described my invention, what I claim as new and desire to secure by Letters Patent is:

1. In a silo having a door opening, a metal frame of hexagonal form adapted to seat against the silo wall and reinforced with braces positioned to lie along the edges of a door opening, and means for attaching a tightening rod to opposite edges of said frame.

2. In a silo having a door opening, a rigid metal frame adapted to completely encircle a door opening and reinforce all four 85 of its edges, said metal frame having upstanding plates adapted for adjustable attachment to the ends of a tightening rod encircling said silo.

3. In a silo having a rectangular door 90 opening, a rigid metal frame shaped to completely encircle said opening and reinforce it on all four of its edges, said frame having its sides extended outward for adjustable attachment to the ends of a reinforcing silo 95 tie-rod.

4. In a silo having a rectangular door opening, a metal frame of hexagonal form reinforcing the top and bottom edges of said opening, stiffening bars crossing said frame 100 and shaped to lie against the side edges of said opening, and upstanding plates at the opposite sides of said frame perforated to receive the ends of a tie-rod encircling the silo.

5. A reinforcing frame for silo doors comprising a pair of metal bands connected together at their ends by angle plates and bent to hexagonal outline and reinforcing bars connecting said bands to stiffen the frame, said bars being positioned to lie directly against the edges of a door opening when said frame is in position, and perforations through the upstanding edges of said angle plates for receiving and adjustably securing the ends of a silo encircling tie-rod.

6. A silo door frame adapted to reinforce the door opening at all of its edges and comprising a pair of metal bands connected together at their ends with angle plates bent transversely to receive the offset ends of said bands, the structure so formed being of hexagonal outline and shaped to lie directly in contact with the outer face of the silo, means for securing the ends of a tie-rod to the upstanding edges of said angle plates, and reinforcing bars connecting said bands and having their ends offset to allow the bars to contact directly with the silo wall at the opposite edges of the door opening.

7. The combination of a silo wall built up of cement slabs and having a door opening formed between a pair of wide blocks, of a hexagonal metal frame completely encircling said door opening and lying directly in contact with the silo wall at the top and bottom edges of said opening and extending laterally far enough to reinforce an adjacent stave, of cross bars in said hexagonal frame 5 lying in reinforcing position at the edges of the door opening, and a rod encircling said silo and having its ends adjustably connected with the sides of said hexagonal frame to stiffen the walls of the silo in alignment with the door opening and to hold said frame in its reinforcing position with respect to the edges of the door opening. 15

In witness whereof, I hereunto subscribe my name to this specification in the presence of two witnesses.

SIGURD E. ANDERSON.
